UNITED STATES PATENT OFFICE.

ARTHUR RAUTENBACH, OF SOLINGEN, GERMANY.

CASTING AND MOLD THEREFOR.

1,396,341.

Specification of Letters Patent. Patented Nov. 8, 1921.

Application filed July 27, 1920. Serial No. 399,342.

To all whom it may concern:

Be it known that I, ARTHUR RAUTENBACH, a citizen of the German Republic, and resident at Solingen, Germany, have invented 5 certain new and useful Improvements in Castings and Molds Therefor, (for which I have filed application in Germany Dec. 3, 1917; Jan. 24, 1919; Austria, June 28, 1918; Hungary, July 9, 1918; Czechoslovakia, 10 Jan. 20, 1919,) of which the following is a specification, reference being had therein to the accompanying drawing.

This invention relates to casting and iron molds therefor.

15 As is well known, aluminum pistons for internal combustion engines are subjected to severe service with consequent quick wear.

It is the object of this invention to so 20 cast the pistons as to avoid air holes or cracks and to insure greater rigidity and density, smoother surfaces, and complete uniformity of the separate castings.

Figure 1 is a vertical section through the 25 mold.

Fig. 2 is a top plan with a portion broken away.

Fig. 3 is a vertical section of a modified form.

30 Fig. 1 of the drawing shows a construction of a mold ready for casting in substantially central vertical section, and Fig. 2 shows the same in plan. In these drawings, *a* indicates the outer mold of iron, *b* the core of sand, *c* the pouring holes, *d* and *e* the risers, *f* and *g* the projections of the core which form the openings for the eyelets of the piston bolts. *h* indicates the hollow space by the filling of which with molten 35 metal the article to be cast is produced.

40 If it be desired to apply specially resistant material at particularly severely strained parts of the aluminium casting, for instance such as bearings of steel, then these 45 can be fixed in the sand core, so that on the casting of the article they are firmly embedded in the aluminium; for instance, the boxes *i* and *k* may be inserted in the projections *f* and *g*.

50 From this description the operation of the invention will be readily understood without much further explanation.

On casting the metal, which flows through the pouring hole *c* of the sand core 55 *b* into the hollow space *h*, as dry sand is a very poor conductor of heat, the metal loses

but very little heat in its passage through the sand core, and it experiences no serious cooling up to the moment in which it reaches the hollow space *h*, in which space it must 60 solidify. In consequence of the slight losses of heat on the way from the ladle to the space *h*, the metal in the furnace need not be overheated, which was always necessary when it had, before entering into the mold, 65 to pass through a pouring hole or funnel of iron, because in this manner even when the funnel was previously heated much heat was lost. The overheating of the metal, as is well known, is a frequent cause of bad castings. Moreover, overheated metal tends to 70 eat into the iron mold and reduce its service in a quite extraordinary manner.

The central position of the pouring hole 75 enables the fluid metal to cover the bottom of the mold quite uniformly and, rising slowly, fill the mold. In consequence of the uniform rise of the metal there is attained a quite uniform cooling and setting of the same, whereas formerly, through the introduction of the fluid metal sidewise to the bottom or to one side surface of the mold, this part was very strongly heated at the pouring place. By reason of this one-sided heating, there occurred, on cooling, strains 80 which frequently led to cracks in the casting and also in the mold. By pouring through the centrally located pouring hole, the metal fills the mold from below, rising without resistance and driving the air in front of it, which air escapes at *d* and *e*. In the previously side casting system, the metal flowed against the core and frequently took up air bubbles from it, which the cooling metal could no longer liberate, and which then formed flaws in the finished casting. On cooling, the solidified metal 85 closes around the yielding sand core, whereas the formerly employed rigid iron core, if it could not immediately, and before the cooling and contraction began, be removed 90 from the mold, was firmly inclosed by the casting or even burst the same.

The above described arrangement renders 105 possible the use of a mold in one piece, whereas previously, in view of the pouring device, a division of the mold was necessary. The present invention may be usefully employed not only for aluminium and aluminium alloys, but also for all metal castings 110 of low melting point, especially also for magnesium and magnesium alloys.

It was stated above that if desired a more resistant material might be inserted at the parts of the aluminium casting subjected to special wear, for instance bushes or journals of steel, which articles were to be attached to the sand core so that they could be firmly incorporated on casting in the aluminium, this being effected by inserting the steel articles on projections of the sand core.

10 As in the application of said bushes or journals in the casting the future working depends on having the journals at both sides situated exactly on one and the same axis, and further that this axis may rest exactly perpendicular to the piston axis, care must be taken, on the shaping of the core and the setting thereof in position in the shell, to have the journals in the correct position. This operation however presents difficulties inasmuch as the sand core, during the drying, warps and twists in an uncertain and indeterminable manner, so that the axes of the inserted journals become displaced with regard to one another. The 25 drawbacks of this condition are then discovered during the further operations, because a uniform boring of the journals is not possible. This moreover further influences the necessary balance of the weight of 30 the piston in the case of multiple cylindered engines.

In order to obviate these drawbacks, the present improvement is devised whereby the bearings or journals to be cast into the piston are placed upon projections which are inserted from the outside through openings in the walls of the shell into the casting space of the mold. These projections are preferably placed in slightly tapering borings of the shell wall and can obviously be attached with complete exactness so that their axes coincide. The journals then rest upon the inner limbs of these projections exactly at the right place. In order, however, 45 still more to increase the exactitude, there are formed in the sand core annular disks, the borings of which (preferably slightly tapering) serve as inner supports for the projections inserted from the outside. In 50 this manner the exact position of the journals is doubly assured, and, moreover, there is attained the result that the parts of the casting projecting inward in the cylinder,

and surrounding the journals, have as uniform thickness as possible and do not become eccentric to the journals.

The supporting projections of the journals inserted from the outside are removed immediately after the setting of the casting and while the casting is still as hot as possible, in which condition they are easily drawn out of the box.

The drawing illustrates in Fig. 3 the casting mold of this kind in section.

a consequently indicates the shell mold, *b* the sand core, *c* the pouring holes, *h* the hollow space for pouring the metal, *i* and *k* the journals to be cast in the mold constructed of stronger material. At two opposed points there are provided in the mold, 70 on one and the same axis, wall perforations of slightly tapering form which serve for the insertion of the bolts *m*. These are provided at their inner ends with cylindrical projections *n*, for the reception of the journals *i* and *k*. At the ends of these projections there are provided also short conical pieces *o*, which fit in corresponding recesses of the annular disk *p* connected with the sand core.

What I claim is:

1. In a mold for the purpose described, a shell provided with coaxial borings for the insertion of bolts, and bolts therein having at their inner ends cylindrical projections 85 adapted to bear upon the inner projections of the journals which are to be incorporated in the casting.

2. In a mold for the purpose described, a shell provided with coaxial borings for the 90 insertion of bolts, bolts therein having at their inner ends cylindrical projections adapted to bear upon the inner projections of the journals which are to be incorporated in the casting and conical pieces at the ends 95 of said projections, and a sand core having at the bearing points of the axle boxes annular rings for the reception of short conical pieces.

In testimony whereof I affix my signature in the presence of two witnesses.

ARTHUR RAUTENBACH.
